UNITED STATES PATENT OFFICE.

DOMINGO BRESCIA, OF QUITO, ECUADOR.

DEVICE FOR CHARGING CAPSULES.

980,756.

Specification of Letters Patent.

Patented Jan. 3, 1911.

Application filed April 29, 1910. Serial No. 558,437.

To all whom it may concern:

Be it known that I, DOMINGO BRESCIA, a subject of the King of Italy, and a resident of Quito, in the Republic of Ecuador, South America, have invented a new and Improved Device for Charging Capsules, of which the following is a full, clear, and exact description.

This invention relates to devices for charging capsules with carbonic acid gas or the like, the capsules being automatically sealed when charged and opening automatically when applied to a siphon, to permit the gas to escape from the capsule into the siphon to mingle with the liquid in the latter, and relates more particularly to a device of this class which comprises a charging vessel having a suitable valve-controlled inlet and a similar controlled outlet for the gas, the vessel being pivotally mounted so that it can be reversed, and having reversible baskets or trays mounted in a basket-carrier within the vessel and each serving to properly position the capsules for charging.

An object of the invention is to provide a simple, inexpensive and durable device for charging capsules of the class described with carbonic acid gas or gas of similar character, which is simple in operation, which can be easily controlled and which requires no skilled labor for its manipulation.

A further object of the invention is to provide a device of the class described in which a large number of capsules can be charged at one time, into which the capsules can be inserted and from which they can be removed expeditiously and with little trouble and which is compact in form.

The invention consists in the construction and combination of parts, to be more fully described hereinafter and directly set forth in the claims.

Reference is to be had to the accompanying drawings forming a part of this specification, in which similar characters of reference indicate corresponding parts in all the figures.

Figure 1 is a longitudinal section of an embodiment of my invention; Fig. 2 is a plan view of the same; Fig. 3 is a longitudinal section of a capsule, showing the same in position in the charging vessel, the capsule being in its initial position; Fig. 4 is a similar view showing the capsule inverted and in a secondary position, which permits

the valve of the capsule to close automatically; Fig. 5 is a perspective view of one of the baskets for the reception of the capsules during the charging process; Fig. 6 is a perspective view of a basket removed from the charging vessel; and Fig. 7 is an enlarged fragmentary cross section, showing a detail of construction.

Before proceeding with a more detailed description of my invention, it should be clearly understood that while the device is particularly useful in charging capsules of the construction described above, it can also be advantageously employed for charging capsules or like containers of different form, provided these containers are valve-controlled so that they can be automatically closed by inverting the charging vessel of the device or by some similar operation.

The charging device is particularly useful in connection with the capsules shown and described in my patent application, filed June 12, 1908, under the serial number of 438,088. These capsules have valve-controlled openings which are automatically opened when the capsule is applied to the spout of a siphon, to permit the gas to escape from the capsule to enter the siphon and there to mingle with the liquid which is to be charged.

Referring more particularly to the drawings, I provide a charging vessel A mounted upon a base A' of any suitable construction and having parallel standards A². The latter have laterally-extended feet A³ held in suitable recesses in the base of the vessel A by means of screws or bolts A⁴ or in any other suitable manner. These standards A² are provided at their upper ends with bearings 10. The charging vessel has corresponding tubular trunnions 11, shown most clearly in Fig. 1, and movably engaging at the inside of the bearings 10. A supply pipe 12 extends through one of the bearings 10 and is screwed or otherwise secured to one of the trunnions 11, while a discharge pipe 13 is similarly mounted in the other bearing 10 and is likewise secured to the other trunnion 11 of the charging vessel A. The connections between the pipes 12 and 13 and the vessel A are such that the vessel can be readily disconnected from these pipes when desired. The pipes 12 and 13 are prevented from shifting when the vessel 110 is revolved by nuts 14 which are preferably flanged. A flexible tube 15 connects the

inlet pipe 12 with a source of liquid carbonic acid gas supply, and a suitable pump or other device is coupled to this supply means for forcing the gas into the vessel 5 under pressure. A gage 15^a is positioned upon the pipe 12 and communicates inferiorly therewith to determine the pressure of the gas being introduced into the charging vessel and at the same time to permit 10 the quantity of this gas to be determined if desired.

The pipe 12 is provided with a suitable valve 12^a and the pipe 13 with a corresponding valve 13^a. These valves control the flow 15 of gas through the respective pipes. The pipe 13 is an exhaust or a discharge pipe and has a connection 16 with a reservoir of any desired type.

The charging vessel A is preferably of 20 cylindrical form and like the remaining parts of the device can be fashioned of any suitable material, for example, of metal such as cast iron or brass. At one end the vessel is open and is provided with a cap 18, by 25 preference screwed thereon. The cap is fitted at the inside with a washer or gasket, 19 adapted to seat at the rim of the open end of the vessel to insure a tight closure. The cap has an exterior fin or rib 20, and the 30 opposite end of the vessel carries a corresponding fin 21, as is shown most clearly in Fig. 1.

The base A' has a substantially centrally-disposed recess 24 in which a spring 22 is 35 loosely positioned. The spring is bowed and has intermediate its ends a recess 23 which is adapted to be engaged by one or the other of the fins 20 or 21, depending upon the position of the vessel A. The 40 spring thus serves to hold the vessel in place with either end upward.

Each of the capsules C of the type for 45 which my device is particularly useful consists of a tubular body 34 having opposing exterior ears 35, to facilitate the application to a siphon, and a cap 36 firmly screws on one end of the body. At the opposite end of the body is an open mouthed neck 39 provided with an interior screw thread 40. 50 A central opening is located in the partition between the neck and the body of the capsule and loosely receives the stem 42 of a valve D. This valve within the body of the capsule is provided with a head 43 carrying 55 an elastic packing 44, and within the neck 39 a disk 45 is secured to the valve stem.

The capsules C are packed as closely as 60 possible in baskets or trays B, each of which preferably consists of an annular body 25 having a reticulated or perforated bottom 26 and a suitable brace or braces 27. The bottom of the baskets may consist of any suitable material, for example, of wire netting. The baskets after being filled with 65 capsules are placed one upon the other and

arranged within a basket carrier B'. The latter comprises a circular skeleton body 28 having attached thereto a perforated or reticulated bottom 29, consisting preferably of wire netting, braces 30 arranged transversely of the bottom and a series of uprights or posts 31 strengthened by one or more annular braces 32. Each of two opposing uprights carries therebetween a handle 33 by means of which the carrier 75 can be conveniently manipulated. The carrier is so constructed that it fits snugly within the charging vessel. After the carrier together with the packed baskets has been inserted in the charging vessel, the cap 80 of the latter is screwed into position upon the open end and the vessel is thereby securely closed, being held in the initial position by the spring 22. In the upright or initial positions of the capsules the valves 85 are open and gas can enter the stem when it is introduced into the charging vessel through the inlet pipe 12, the valve 12^a being open for the purpose. By means of the gage 15^a the charging of the capsules with 90 gas under pressure can be easily controlled, the valve 13^a of course being closed during the charging operation. When this operation has proceeded as far as necessary, the valve 12^a is closed and the vessel is inverted, 95 the fin 20 then engaging the holding spring 22. By inverting the vessel the capsules are also inverted and the valves thereof automatically close gravitationally, as is shown most clearly in Fig. 5. The gas is 100 then allowed to escape from the charging vessel, the valve 12^a being closed, and the vessel can then be again inverted. It will be understood that the valves of the capsules cannot then open again owing to the 105 pressure of the gas within the capsules, the pressure at the outside being merely the atmospheric one. The cap is now removed from the vessel and the charged capsules can be taken therefrom.

Having thus described my invention, I claim as new and desire to secure by Letters Patent:

1. A device for charging capsules, comprising a charging vessel adapted to receive 115 gas under pressure, and arranged to be held in a plurality of positions, and baskets for removably holding the capsules within the vessel whereby the valves of the capsules are controlled by the position of the charging vessel.

2. A device for charging capsules having valve-controlled openings, comprising a charging vessel adapted to receive gas under pressure, and means for positioning a plurality of capsules in said vessel whereby the openings of said capsules are initially unobstructed and whereby the openings are closed when the vessel assumes a secondary position.

3. A device for charging capsules having valve controlled openings, comprising a reversible charging vessel adapted to receive gas under pressure, and means for positioning a plurality of capsules in said vessel, whereby in the initial position the openings of the capsules are unobstructed, and whereby in a reversed position of said vessel the opening of the capsules are closed.
- 10 4. A device for charging capsules, comprising a pivotally-mounted charging vessel, a gas inlet and a gas outlet therefor, valves for controlling the supply and discharge of the gas, a basket carrier removably fitted in said vessel, and baskets for the reception of capsules and adapted to be fitted in said basket carrier.
- 15 5. A device for charging capsules, comprising a reversible charging vessel, a gas inlet and a gas outlet therefor, valves for controlling the supply and discharge of the gas, a basket carrier removably fitted in said vessel, and baskets for the reception of capsules and adapted to be fitted in said basket carrier.
- 20 6. A device for charging capsules, comprising a base, a reversible charging vessel carrier, each of said baskets and said basket carrier having a perforated or reticulated bottom, said baskets being arranged one upon the other within said carrier.
- 25 7. A device for charging capsules, comprising a base, standards upon said base having bearings, a vessel journaled in said bearings, a gas inlet extending through one of said bearings and communicating interiorly with said vessel, a gas outlet extending through the other of said bearings and communicating interiorly with said vessel, said vessel having a reversible cap, a resilient member mounted upon said base, and having a recess, said vessel having a plurality of fins adapted to engage said resilient member whereby said vessel can be held in any one of a plurality of positions, and baskets for removably positioning the capsules within said vessel.
- 60 In testimony whereof I have signed my name to this specification in the presence of two subscribing witnesses.
